UNITED STATES PATENT OFFICE.

REYNOLD JANNEY, OF NEW YORK, N. Y.

CONTROLLING APPARATUS FOR FLUID-GEAR.

1,220,424.

Specification of Letters Patent. Patented Mar. 27, 1917.

Application filed September 16, 1911. Serial No. 649,698.

To all whom it may concern:

Be it known that I, REYNOLD JANNEY, a citizen of the United States, residing at New York, in the county of New York and 5 State of New York, have invented certain new and useful Improvements in Controlling Apparatus for Fluid-Gears, of which the following is a specification.

This invention relates to controlling apparatus for hydraulic variable speed gear devices, the object of the invention being to provide positively-acting means by which the transmission of power can be effectively governed.

15 In the drawings accompanying and forming part of the present specification I have shown in detail several of the many forms of embodiment of my invention, which to enable those skilled in the art to practice the same will be set forth fully in the following description, while the novelty of the invention will be included in the claims succeeding said description. From this observation it will be evident that I do not restrict myself to such disclosure; I may depart therefrom in many respects within the scope of the invention included in the claims following said description.

Referring to said drawings:

30 Figure 1 is a side elevation of controlling apparatus involving my invention and showing the same operatively associated with a hydraulic speed gear device of familiar type.

35 Fig. 2 is a side elevation partially in section of the upper portion of said device controlling mechanism.

Fig. 3 is a vertical section of the inner portion of a compensating sleeve, the upper 40 part of a tilting box, and certain adjunctive devices hereinafter more particularly described.

Fig. 4 is a vertical, transverse section on the line 4—4 of Fig. 2.

45 Figs. 5 and 6 are views corresponding to Fig. 2 and show modifications hereinafter more fully described.

The several views, it will be perceived, are on different scales and throughout the 50 same like characters refer to like parts.

As will hereinafter appear my controlling apparatus operates usually in conjunction with a regulator which may be shifted to obtain different relations in a hydraulic variable speed gear device. This regulator may vary decidedly as to character and func-

tion. It may, as illustrated, although this is not essential, consist of what is known in hydraulic variable speed gear devices as a "tilting box." A hydraulic variable speed gear device ordinarily comprises a pump section or end, and a hydraulic-engine section or end, and it has been the practice to relate these two sections or ends in a great many different ways which it is needless for me to describe as my invention does not concern these. In Fig. 1 of the drawings, however, I have represented one hydraulic variable speed gear device of known kind, the same being substantially similar to that shown in Letters Patent No. 924,787 granted to me June 15, 1909, and to which reference may be had. In said Fig. 1 the numeral 5 denotes the pump end or section of the device while the numeral 6 represents the hydraulic engine end or motor section thereof, and while as already indicated it is usual to arrange these portions in many different ways, they are as illustrated coaxial, their shells or cases abutting against the intermediate valve or mid plate 7 and the several parts being bolted or otherwise suitably connected to each other. The casing or shell of the pump end or section 5 encloses a tilting box as 8, the oscillation or rocking of which is utilized to vary or change the stroke of the pump pistons in the pump end or section 5 to thereby correspondingly vary the speed of or to reverse the pistons in the hydraulic engine end or section 6. The tilting box 8, therefore, presents a regulator for an engine or motor, it primarily regulating the pump or pumps, and through the latter, the engine or motor. While as shown this regulator is adapted to effect changes in speed or direction of motion, these may not in all cases be essential. The pump end 5 of the device supports a rotary shaft 9, which is generally continuously driven and for this purpose any desirable means may be provided, for instance an electric motor which is not illustrated. The hydraulic engine end sustains a shaft 10 which is rotated by the pistons of the hydraulic engine 6. The foregoing is a brief description of a hydraulic variable speed gear device such as shown in Fig. 1 and which is approximately similar to that disclosed in the Letters Patent to which I have already alluded. It will be obvious that my invention does not reside in such a device but rather in controlling

means therefor, although as I state this controlling means may be employed in other ways.

I will now describe in detail a controlling mechanism which is quite satisfactory, but before doing so I wish to make it clear that I do not restrict myself to such showing.

A control shaft housing as 11 is supported by and in communication with the case or shell of the pump end 5 and in it has screwed or otherwise fitted into it the control-shaft hanger-piece 12. I have shown as connected with said hanger piece 12, the bearing piece 13 and the lock nut 14 which with the several parts associated therewith, constitute a stuffing box through which the control shaft 15 extends, said shaft being sustained by the hanger and bearing pieces to which I have just referred. Said control shaft 15 is illustrated as provided with a rigid collar 16 engaged at opposite sides by washers 17 which are usually made of some fibrous material and which are held in place by the hanger piece 12 and bearing piece 13, by virtue of which endwise movement of the control shaft 15 is prevented. As will hereinafter appear, this control shaft is operatively connected with the tilting box 8 in such way that when the shaft is rotated the tilting box will be swung to either vary the stroke of the pistons in the pump end or to reverse the same and such an operative connection as will be understood can be obtained in many different ways. It is equally conceivable that the control shaft in some cases might not actually be in the form strictly speaking, of a shaft and therefore when I use the term "control shaft" it will be evident that I do so in a generic sense, intending thereby to cover various devices by which the position of a tilting box or some analogous result can be effected to obtain the necessary action. The hanger piece 12 and its associated parts are shown connected with one end of the control shaft housing 11, while in the other end thereof is represented as fitted a bearing piece 18 provided with a stuffing box 19 through which a compensating sleeve as 20 herein-after more particularly described, extends. The housing 11 has a threaded opening 21 to receive the oil-expansion box 22 which is common in this type of apparatus.

The control shaft 15 may be operated in any suitable manner, although it is my custom to operate the same by hand, the force of which may be applied thereto either directly or indirectly as shown. The hand wheel 23 for instance may be utilized for this purpose, said hand wheel being rigidly connected with the shaft 24, the housing 11 having an arm 25 to support said shaft 24. The effect of the manually-operable shaft 24 may be applied to the control shaft 15 in divers ways, for instance, through

gearing, the gearing shown for this purpose being of bevel type. Keyed or otherwise suitably fastened to said shaft 24 is a bevel gear 26 in mesh with the bevel gear 27 keyed or otherwise suitably connected with the control shaft 15. When, therefore, the hand wheel 23 is rotated the control shaft 15 through the intermediate connections, will be also similarly rotated whereby the tilting box 8 will be oscillated.

The control shaft 15, as will be understood, extends through the bearing piece 13 and the hanger piece 12 into the control shaft housing 11, the inner end of said shaft being shown as threaded to fit threads in the compensating sleeve 20 to which I have already briefly referred, said compensating sleeve projecting from the casing through the bearing piece 18. The threaded or feed connection between the compensating sleeve 20 and the control shaft 15 is as illustrated, within the control shaft housing 11. The threaded or nut portion of the compensating sleeve 20 is represented as provided exteriorly thereof with an annular collar 28 which may be integral therewith, and also with lock nuts 29 and 30 threaded thereonto, the trunnioned sleeve 31 being held between said collar 28 and lock nuts 29 and 30. The compensating sleeve 20 may be rotated in the trunnioned sleeve 31 by means hereinafter described, and on this motion said trunnioned sleeve, as will be apparent, will be moved longitudinally of the control shaft 15. The oppositely-disposed trunnions 32 of the sleeve 31 have freely fitted to them, guide blocks 33 which as shown relatively slide between the fingers of the tilting box extension 34, said extension 34 being usually made as a yoke and the branches thereof being slotted or forked to present two pairs of fingers between which the respective guide blocks 33 are disposed. The trunnions 32 in addition to the guide blocks 33, have a second pair of guide blocks 35 also loosely carried thereby and which are adapted to travel along longitudinally-extending grooves 36 in the control shaft housing 11 all as shown in Fig. 4. It will, therefore, be evident that in view of the connections set forth the tilting box 8 can be operated by means of the control shaft 15 when the same is rotated as already described, to effect the change in stroke of the pistons in the pump end or to reverse the movement of such pistons.

The tilting box is adapted to occupy a neutral, zero or ineffective position as shown in Fig. 2, and when in this position the pistons in the pump end and in the engine end are at a state of rest. As the tilting box 8 is swung from this neutral or zero position to an engine-starting or effective position, the pistons at the pump end 5 will be reciprocated thereby reciprocating the pistons in

the engine or motor end 6, the strokes of the respective sets of pistons increasing in proportion to the movement of the tilting box from the neutral position, by reason of which the shaft 10 will be rotated and its speed thereafter increased as is common. As will hereinafter appear I provide separate or independent means which tend to return the tilting box to neutral or zero position, such means acting in opposition to the manual or other force applied to the control shaft 15 to shift the tilting box into piston-reciprocating position, and in the present case this opposing effect is virtually continuous, although not essentially, and while it can be accomplished in different ways automatically by the power of the device, it is advantageously secured through the agency or aid of the compensating sleeve 20 as will hereinafter appear.

The compensating-sleeve 20 has interiorly thereof the polygonal portion 37 to receive the polygonal portion 38 of the shaft 39 supported for rotation by the arm 40 on the casing or shell of the engine section 6, and both polygonal portions are shown as square, by reason of which when the shaft 38 is turned the compensating sleeve 20 will be correspondingly operated. The shaft 39 is what might be considered a power engine-operated shaft, being continuously rotative or rotated as long as the engine 6 is in action, and this result may be secured for example by operatively connecting the shaft 39 with the shaft 10 for instance by gearing, said shaft 39 being shown as equipped with a spur gear 41 in mesh with a pinion 42 rigid with the shaft 10. The gear 41 and the collar 43 on the shaft 39 jointly prevent said shaft 39 from moving in an endwise direction or longitudinally. While the inner end of the shaft 38 is in proximity to the inner end of the control shaft 15, these two shafts have no direct connection, although they are operatively connected or indirectly so through the compensating sleeve. It will be understood that the instant the control shaft 15 is operated to shift the tilting box 8 from its neutral or zero position, opposing means is automatically thrown into action and which tends to return said tilting box to said neutral position. With this preliminary statement, I will describe briefly the action of the apparatus and certain points connected therewith. When the control shaft 15 is operated, the compensating sleeve 20 owing to its described connection with said shaft, will be moved longitudinally carrying with it the sleeve 31 and thereby tipping through a certain angle, the tilting box 8. As soon as said tilting box is thus operated the shaft 10 commences to operate whereby the shaft 39 through the gearing referred to will be also rotated. The compensating sleeve 20 is also rotated by the squared shaft

39. I might state at this time that the gearing between the shaft 10 and the shaft 39 should preferably be such as to always cause said shaft 39 to rotate in the same direction as the control shaft. It will be understood that if the control shaft 15 be rotated in one direction to cause the compensating sleeve 20 to move endwise, the rotation of the squared shaft 39 will be such as to cause said compensating sleeve to rotate in such direction as to counteract the effect of the control shaft, the constant tendency being while the device is in action, to bring the compensating sleeve and necessarily the tilting box back to a mid or neutral position at which point the pistons of the pump end or section will not be reciprocated. If the control shaft 15 be turned rapidly so as to tilt or tip the tilting box into any desired position and be then stopped, the rotation of the shaft 10 will be such as to operate the squared shaft 39 to bring as already described, the tilting box to its neutral or zero position. In theory the time required for the compensating sleeve to return to its neutral position will be infinite, because as it approaches its neutral position the speed of the shaft 10 becomes less and less and consequently the movement of the compensating sleeve becomes slower and slower. Practically, however, said compensating sleeve is returned to a point very near its neutral position quite rapidly and if the operator aids the movement by a slight reversal of rotation of the control shaft, said compensating sleeve will be brought to its zero or neutral position as quickly as desired. If the operator rotates the control shaft 15 in either direction the action of the shaft 10 will be such as to cause the compensating sleeve to tend to counteract such rotation to overcome which it is necessary that the operator keep a little ahead of the compensating action. It follows, therefore, that the faster the operator rotates the control shaft the greater will be the degree of angular movement of the tilting box and hence the greater will be the speed of the shaft 10. The mechanism therefore provides a means for controlling the speed of the shaft 10 or its equivalent by the rate at which the hand of the operator causes the control shaft to move and not simply by the angular position which he causes the control shaft.

In hydraulic transmission gear devices of the type hereinbefore referred to the speed and direction of movement of the shaft 10 from which power is to be derived, are usually determined merely by the rotation of the control shaft to a limited degree in one direction or the other, the angle of rotation of said control shaft determining positively the speed of the shaft 10 or some analogous part and the direction of this angular movement determining the rotation of the shaft 10 or the like. By mechanism involving my

invention, however, the mere angle of rotation of the control shaft does not determine the speed of the shaft 10. As a matter of fact the control shaft may be rotated continuously while the shaft 10 only turns very slowly, the effect which is the very important point, depending generally on the rate of speed at which the control shaft is turned and not on the angular distance through which it is turned. If, therefore, the control shaft be turned very rapidly through any angular distance, this angular distance will determine the maximum momentary speed of the shaft 10 which speed, however, rapidly falls toward zero through the action of the compensating sleeve in the manner already described. I might add in conclusion that the shaft 10 can operate various kinds of apparatus such as ships' turrets, guns, rudders, etc. It is also desirable to add that I can continuously operate the control shaft or its equivalent in either direction at varying speeds according to the desired speed of said shaft 10, the latter at all times when in action tending constantly to counteract the effect on the tilting box or analogous member by the continuous rotation of said shaft; in other words there is a tendency of the engine operated shaft 10 constantly to catch up as it were with the control shaft when the same is being rotated manually or otherwise.

The foregoing description applies particularly to the showing made by Figs. 1 to 3 inclusive. I have already intimated that I may use the controlling mechanism in various connections, and in Figs. 5 and 6 which will hereinafter be described in succession I show two forms of controlling mechanism different from each other and from the construction already described fully. These several modifications illustrate that the details of construction and arrangement may vary considerably without departing from the general principles involved. I might also mention that in all cases it is not essential that the controlling mechanism be employed in conjunction with a hydraulic variable speed gear device as it may be used with equal advantage in connection with other kinds of fluid governed or operated apparatus or machines.

Referring now more particularly to Fig. 5: In this particular view the control shaft and counter control shaft are combined into one, said combined control and counter control shaft being denoted by 44. What might be considered the controlling end of said shaft is at the left, while the counter controlling end thereof is at the right in said figure, although this is not at all essential. In the construction shown by said Fig. 5, there is a compensating member but strictly speaking the same does not take the form of a sleeve, said compensating member being

made as a gear 45 supported for rotation by the arm 40, the same in construction as the part already described bearing such numeral. The gear 45 as shown is immovable in the direction of its axis of rotation and has a feed connection with the shaft 44. In the present case the counter controlling portion of said shaft is threaded as at 46, said threaded portion 46 extending through the gear 45 and engaging corresponding threads within said gear. The controlling portion of said shaft 44 extends through the housing 11, the ends of which may be provided with stuffing boxes as 47 and 48. Around the controlling portion of the shaft 44 in the housing 11 is a trunnioned sleeve 49 constructed like the trunnioned sleeve already referred to, and held against movement on said shaft 44 longitudinally thereof by collars 50 and 51. The trunnioned sleeve 49 is connected with the tilting box 8 in the manner already described. The engine operated shaft 10 is equipped with a gear 42 as already described. This gear 42, however, is not connected directly with the gear 45 but is indirectly connected therewith through the intermediate gear 52, by reason of which the gear 45 will be rotated in the proper direction. The action of the construction shown in Fig. 5 briefly set forth is as follows: When the shaft 44 is turned through the agency of the hand wheel 53 connected directly therewith or in some other suitable way, said shaft is drawn endwise by virtue of its threaded connection with the gear 45 thereby moving the trunnioned sleeve 49 therewith and giving to the tilting box 8 the necessary controlling movement. On the shifting of said tilting box the shaft 10 will, as will be understood, be rotated thereby through the described gears 42 and 52 rotating the gear 45. As said gear 45 is thus turned, the shaft 44 will be given a movement endwise to that when the shaft 44 is directly turned assuming of course, that the shaft 44 is not allowed to turn with the gear or wheel 41. The construction shown in Fig. 5 provides a means for the continuous turning of the shaft 44 as already explained in connection with Figs. 1 to 3 inclusive.

Referring now to Fig. 6: In this organization the control shaft 54 extends through the housing 11 through stuffing boxes 47 and 48. The control shaft 54, however, is separate from the counter controlling shaft 55, although the two shafts are operatively connected as will hereinafter appear. The control shaft 54 is threaded as at 56 to receive the nut 57 provided with trunnions 58 operatively connected with the tilting box 8 in the manner already described. The controlling shaft 54 may be equipped with a hand wheel 59 by which the same can be rotated to effect the movement of the tilting box 8 to its several controlling or governing

positions. I might mention that part of the controlling shaft 56 which is within the housing 11 is threaded for the greater part of its length.

5 The outer end of the counter controlling shaft 55 is threaded as at 60, the said threaded portion 60 extending through and being connected with threads within the gear 61 supported by the arm 40. The gear 10 61 like the gear 45, although rotary, is immovable in the direction of its axis of movement. The supporting arm 40 is provided with a key 62 to enter a longitudinally extending spline or keyway 63 in the 15 counter controlling shaft 55 to prevent rotation of said shaft 55, although it is clear that the latter may be moved endwise. The two shafts 54 and 55 are connected together by the coupling sleeve 64 and the heads or 20 flanges 65 and 66 at the ends of the respective shafts 54 and 55 by reason of which the control shaft 54 can rotate independently of the shaft 55, although the two must move together endwise. In mesh with the 25 gear or pinion 61 are teeth 67 cut at the upper end of the piston rod 68, the piston or plunger 69 of which is adapted to reciprocate in the cylinder 70 or equivalent casing inlets for fluid opening into said cylinder or casing 70 at opposite sides of said piston 69 and being denoted by 71 and 72 respectively. The ducts or inlets 71 and 25 72 are adapted for connection with any suitable fluid actuated apparatus such for example as the pump section of a device of the type already described.

Briefly the operation of the construction shown in Fig. 6 is as follows: By turning the control shaft 54 through the hand wheel 40 59, the nut 57 will be moved along said shaft 54 thereby to operate the tilting box 8. When this occurs fluid from the pump section will be caused to enter the casing or cylinder 70 by way of one or the other of the ducts 71 and 72 from the pump section to thereby operate the piston 69 and hence the piston rod 68. When this occurs the gear 61 is rotated and by reason of its feed connection with the counter control 45 shaft 55, said counter control shaft is moved endwise and through the coupling sleeve 64 moving the control shaft 54 in a corresponding direction and consequently moving the nut 57 in a direction opposite to that it follows when the control shaft 54 is turned. I might mention that in the construction shown in Fig. 6 continuous rotation of the control shaft 54 is not provided for, the controlling effect, however, being secured by giving to the control shaft a definite number of turns. There is also a fixed relation between the amount of movement of the piston 69 and the number of turns of the control shaft 54. An arrangement of this kind is necessary where

said piston is to be moved only a prescribed distance and then left for a time in its shifted position or returned to its original or any other desired point. The speed of movement of the piston or equivalent part, 70 however, is not, therefore, an important element to be considered. It might also be stated that the structure shown in Fig. 6 is adapted to be applied to a mechanism where the nut 57 or equivalent part is intended to control the supply of fluid to the ends of a cylinder as 70 by way of pipe connections 71 and 72 or in practically similar fashion.

What I claim is:

1. In an apparatus of the class described, the combination of a hydraulic variable speed gear device having an engine section and a pump section, and also having a regulator for governing the action of the pump section, means for moving said regulator from a neutral or pump stopping position to a pump starting position to thereby start said pump and therefore said engine, and independent means for returning said regulator to said neutral position.

2. In an apparatus of the class described, the combination of a hydraulic variable speed gear device having an engine section and a pump section, and also having a regulator for governing the action of the pump section, means for moving said regulator from a neutral or pump stopping position to a pump starting position to thereby start said pump and therefore said engine, and independent means operative by said engine for returning said regulator to said neutral position.

3. In an apparatus of the class described, the combination of the tilting box of a hydraulic variable speed gear device, said tilting box being movable from a neutral or ineffective position to an effective position, means for moving said tilting box from said neutral position to said effective position, and independent means for returning said tilting box to said neutral position.

4. In an apparatus of the class described, the combination of the tilting box of a hydraulic variable speed gear device, said tilting box being movable from a neutral or ineffective position to an effective position, means for moving said tilting box from said neutral position to said effective position, and independent means operative by said hydraulic variable speed gear device, for returning said tilting box to said neutral position.

5. In an apparatus of the class described, the combination of the tilting box and control shaft of a hydraulic variable speed gear device, a movable member to which said shaft is operatively connected, said shaft being rotative in either direction and being adapted to shift said movable member

to tip said tilting box from its neutral position and thereby cause the operation of said gear device, and means automatically thrown into action by and on the movement of said 5 tilting box from said neutral position, for counteracting the effect on said movable member by the operation of said control shaft.

6. In an apparatus of the class described, 10 the combination of the tilting box and control shaft of a hydraulic variable speed gear device, a movable member to which said shaft is operatively connected, said shaft being rotative in either direction and being 15 adapted to shift said movable member and thereby tip said tilting box from a neutral position to a position where it will cause the operation of said gear device, and means automatically thrown into action by and on 20 the movement of the tilting box from said neutral position and operative by the power of said device, for counteracting the effect on said movable member by the operation of said control shaft.

- 25 7. In an apparatus of the class described, the combination of a hydraulic variable speed device comprising means for starting the same, and independent means active in opposition to said other means and tending 30 to stop said device.

8. In an apparatus of the class described, the combination of a hydraulic variable speed gear device comprising manually governed means for starting said device, and 35 independent means automatically thrown into action when said device is started, active in opposition to said other means and tending to stop said device.

9. In an apparatus of the class described, 40 the combination of a hydraulic variable speed gear device comprising a pump section and a regulator connected with said pump section, said regulator being shiftable from a neutral or pump stopping position 45 to a pump starting position, a rotary control shaft, a compensating sleeve having an endwise movable feed connection with said control shaft, and operatively connected with said regulator, and means independent 50 of said shaft for rotating said compensating sleeve.

10. In an apparatus of the class described, the combination of a hydraulic variable speed gear device comprising a pump section 55 and an engine section, said pump section having associated therewith a regulator shiftable from a neutral or pump stopping position to a pump starting position whereby when the pump is started the engine will 60 be operated, a rotary control shaft, a compensating sleeve having a rotary, endwise movable feed connection with said control shaft and operatively connected with said regulator, and means independent of the 65 control shaft and actuated by said engine

section for operating said compensating sleeve so as to tend to counteract the endwise movement.

11. In an apparatus of the class described, the combination of a hydraulic variable speed gear device having a pump section and an engine section and also having a tilting box connected with said pump section, said tilting box being movable from a neutral or pump stopping position to a pump starting position, the pump when started serving to operate the engine, a rotary control shaft, a compensating sleeve having a rotary, endwise movable feed connection with said control shaft and operatively connected with said tilting box, and means operative from the engine section, for rotating said sleeve in the same direction as said control shaft.

12. In an apparatus of the class described, 85 the combination of a hydraulic variable speed gear device having a pump section and an engine section and also having a regulator connected with said pump section, said regulator being movable from a neutral or 90 pump stopping position to a pump starting position whereby when the pump is started the engine will be operated, a compensating sleeve operatively connected with said regulator to shift the same to its various positions, a control shaft having a connection with said compensating sleeve, for rotating and endwise moving the same, and a shaft operative from said engine connection, having a connection with said compensating 95 sleeve for giving to said sleeve an endwise movement opposite to that produced by said control shaft.

13. In an apparatus of the class described, the combination of a hydraulic variable 105 speed gear device having a pump section and an engine section and also having a regulator connected with said pump section and movable from a neutral or pump stopping position to a pump starting position, a compensating sleeve operatively connected with said regulator to shift the same to its various positions, a rotative control shaft having an endwise movable feed connection with said compensating sleeve, and a rotary 110 shaft operative from the engine section and rotatively connected with said compensating sleeve.

14. In an apparatus of the class described, 120 the combination of a hydraulic variable speed gear device having a pump section and an engine section and also having a regulator connected with said pump section, said regulator being movable from a neutral or pump stopping position to a pump starting position, a control shaft, a compensating member connected with and movable endwise by said shaft, and also operatively connected with said regulator for shifting the same to its various positions, 125 130

and means for countermoving endwise said compensating member in opposition to the effect of said control shaft.

15. In an apparatus of the class described, 5 the combination of a hydraulic variable speed gear device having a pump section and an engine section and also having a tilting box connected with the pump section and movable from a neutral or pump stopping position to a pump starting position, 10 the pump when started serving to operate the engine, said regulator having a yoke, the branches of which are forked to present fingers, a rotary longitudinally immovable 15 control shaft, a rotary compensating sleeve in threaded connection with said control shaft, a trunnioned sleeve fitted around the compensating sleeve and immovable longitudinally thereon, said trunnioned sleeve 20 having oppositely disposed trunnions, two pairs of guide blocks on the said trunnions, one pair of guide blocks being fitted between said fingers, the framing of the machine having grooves to receive the other guide 25 blocks, a shaft rotative by said engine section, and a third shaft geared to said engine

operated shaft and provided with a squared portion, said compensating sleeve having a squared opening to receive the squared portion of said third shaft.

16. In an apparatus of the class described, 30 the combination of a shiftably mounted member mounted for rotary movement and for movement also in the direction of its axis of rotation, a fluid supply regulator operatively 35 connected with said shiftably mounted member, a rotary shaft connected with said shiftably mounted member and adapted to move said shiftably mounted member in the direction of its axis of movement to thereby 40 move said regulator into a fluid supply position, and a counteracting rotatable shaft set in action by the fluid and connected with said shiftably mounted member and acting to counteract the effect thereupon by the 45 first mentioned shaft.

In testimony whereof I affix my signature in presence of two witnesses.

REYNOLD JANNEY.
